(57) **CLAIM**

The ornamental design for a case for wind instrument, as shown and described.

DESCRIPTION

FIG. 1 is a perspective view of the front, bottom and right side of a case for wind instrument showing my new design; FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines show portions of the case for wind instrument that form no part of the claimed design.
